UNITED STATES PATENT OFFICE.

BYRON E. ELDRED, OF BRONXVILLE, NEW YORK, ASSIGNOR TO THE ELDRED & PALMER COMPANY, OF NEW YORK, N. Y., A CORPORATION OF NEW YORK.

PROCESS OF AND APPARATUS FOR BURNING CEMENT.

No. 928,513.

Specification of Letters Patent. Patented July 20, 1909.

Application filed April 30, 1908, Serial No. 430,183. Renewed April 8, 1909. Serial No. 432,738.

To all whom it may concern:

Be it known that I, BYRON E. ELDRED, a citizen of the United States, residing at Bronxville, in the county of Westchester and State of New York, have invented certain new and useful Improvements in Processes and Apparatus for Burning Cement; and I do hereby declare the following to be a full, clear, and exact description of the same, such as will enable others skilled in the art to which it appertains to make and use the same.

This invention relates to process of and apparatus for burning cement; and comprises a process of burning cement clinker wherein cement materials previously calcined and brought to or near a clinkering temperature are clinkered in a rotary clinkering kiln by a relatively small, hot flame of fine fuel burning with the aid of hot air regeneratively heated by the waste heat of said clinkering kiln; and it also comprises certain organizations of apparatus elements adapted for use in the stated process and for like purposes; all as more fully hereinafter set forth and as claimed.

In the prior art it has been customary to perform the various and diverse reactions occurring in the cement kiln with the aid of a single source of heat; generally, with the ordinary rotary kiln, a flame of powdered coal burning in the mouth of the kiln. One of these reactions, the calcination, requires a large volume of heat but does not need a very high degree of temperature while another, the clinkering, presents exactly the opposite requirements. The effort to perform both these reactions with a single source of heat inevitably leads to a waste of fuel. In a prior patent, No. 829,956, Sept. 4, 1906, I have described a method of obviating this waste and securing a number of new advantages, said method consisting substantially in dividing the cement making operation into stages and performing each stage in a separate kiln with the aid of a separate source of heat, each stage being performed under thermal and other conditions best adapted thereto. In another patent, No. 829,957, Sept. 4, 1906, I have described and claimed certain organizations of apparatus useful in the described and similar processes, while in Patent No. 879,448, Feb. 18,

1908, I have described and claimed certain improvements in such apparatus. 55

In the stated patents, and particularly in No. 879,448, the clinkering kiln is shown as heated by producer gas; a fuel which ordinarily does not produce sufficient temperature for such a purpose but in this instance is enabled to do so by burning it hot from the producer with air regeneratively heated by the waste products of the clinkering kiln. With the aid of this sensible heat of gas and air, the temperature of the flame is "stepped up" sufficiently to enable it to keep the clinker kiln at the very high temperature required in clinkering. Regenerators though not ordinarily practicable with the usual cement kilns because of the dust carried forward by the violent rush of flame gases through such kilns incident to the use of a single flame, at once hot enough for clinkering and large enough for calcining, are there practicable for the reason that calcining being performed in a separate kiln, there is little evolution of dust and regenerators do not clog and choke. The temperature planes at the clinkering end and the calcining end of the ordinary kiln are moreover so widely 80 different that there is little utility in employing regenerators heated by waste kiln gases for imparting heat to assist in clinkering. There is however an objection to the use of producer gas in this connection in 85 that somewhat more fuel is required than corresponds to the natural requirements of the operation. In a clinkering kiln operating in my 2-stage process, the thermal conditions are almost static. The calcines come 90 into it from the calcining kiln heated to, or almost to, the sintering temperature and in the clinkering reaction, that is, the union of the lime of the calcines with silica and alumina, little or no heat is absorbed while some 95 is evolved. The only requirement on the clinkering kiln is that it quickly bring these calcines up to the clinkering temperature and maintain the calcines at such temperature until the reaction completes itself. The 100 heat required for this is probably overbalanced by the heat evolved in the reaction. The only important heat losses of the clinkering kiln are those due to radiation and to heat carried away by the finished clinker. 105 Producer gas used in the manner set forth.

in the acknowledged patents will give the required amount of heat and temperature cheaply and conveniently but it suffers several disadvantages, one being that a certain fraction of the heat must be carried away with the products of combustion from the kiln unless the regenerators be also employed to heat other air or gas than that employed in the kiln itself. This is for the reason that for every atom of oxygen used in the producer (or volume of air) to produce gas another atom (or volume of air) must be used to burn this gas. That is, for every volume of air used in the producer another volume of air must be used to burn the resultant gas. The products of combustion formed have the same volume (at the same temperature) as the air used; the amount of such products is equal to the sum of the volumes of the air used in the producer and the air used in burning the gas. Therefore, there will be (neglecting expansion and temperature) two volumes of products of combustion going through the regenerator for every volume of air coming back through the regenerator to be heated, and only half the heat units can be utilized in the regenerator if it be employed to heat only the air used in the kiln.

It is the object of the present invention to obviate even this source of loss of heat in the performance of my described 2-stage cement burning process, and to this end, I rearrange the conditions somewhat and heat the clinker kiln with a flame of fine fuel, preferably coal dust though oil may be used, burning in aerial suspension with the aid of hot air regeneratively heated from the waste gases of such kiln. Theoretically, air in burning carbon does not change in volume, apart from temperature changes, one volume, or molecule, of O_2 uniting with one C to form one volume, or molecule, of CO_2 . That is, air used in burning carbon will have the same volume afterward as before if brought back to the same temperature; and in the case of the clinker kiln heated by burning carbon, the volume of products of combustion will be nearly the same as that of the air used in burning, and a regenerator may be used without the theoretical stated loss of heat. In practice, of course somewhat of an excess of air over theory must be used to secure quick and intense combustion, but this excess appears unchanged in the products of combustion. In heating the clinkering kiln with a flame of fine fuel in this, as in other embodiments of my 2-stage process, regenerators may be safely employed since the calcines do not give off dust in the clinkering kiln to any important extent. In the operation of the ordinary single-fired rotary, the raw cement material, which is always very finely powdered under goes a tumultuous evolution of carbon di-

oxid in the calcining zone and this, in connection with the inordinate rush of gases caused by maintenance of a clinkering flame in the same kiln, causes the waste gases to be heavily laden with dust.

The requirement for heat units in the clinkering kiln being so small when the clinkering kiln is run in connection with a separate calcining kiln, and the heat units being effectively recovered in the regenerator, very little coal is required for heating and the flame employed may be correspondingly small, being merely a short thin flame in lieu of the very long, thick and violent flame of the ordinary single kiln practice. With this short, thin flame the temperature may be very accurately adjusted; something not possible with the violent flames of the single kiln practice. Its position in the kiln may be as desired: axial, impinging or merely inclined. It may be tempered with products of combustion or steam, but this is ordinarily not desirable or useful.

It being difficult to introduce the full amount of air necessary for combustion with the fuel since the fuel cannot be well evenly distributed through such a volume, I prefer to introduce the main bulk of the heated air beside or around the coal jet, introducing merely a portion with the jet. This has the further advantage that, with such hot air as I contemplate using, coking of the coal dust in the injecting nozzle is prevented.

With air introduced at a temperature corresponding to that of the clinkering kiln, or the waste gases therefrom, the combustion of the coal is extremely quick and the temperatures developed are extremely high. Clinkering takes place under temperatures which ordinarily range around 2500° F., or higher. This quick burning, high temperature flame enables me to maintain the desired type of small, thin flame and to meet the requirements of the clinkering kiln with very little expenditure of fuel. The amount of coal so used being so small, naturally I do not contaminate the clinker with any noticeable amount of ash—a great desideratum in this art. Air being introduced into the kiln under pressure while the regenerators oppose a frictional resistance to the outward passage of products of combustion the kiln may be easily run under a slight plenum which prevents access of cold air. As stated, the demands for heat units in the clinkering kiln are largely to compensate for leakage losses and it is highly desirable to prevent such access of cold air aside from the derangement of conditions which such air may cause. The plenum should however be very slight.

The calcining kiln operated in connection with the clinkering kiln may be gas fired or coal fired, but however heated it should be so controlled that calcines are ordinarily de-

livered to the clinkerer in a state of incipient sintering, thereby reducing the demand for heat units in the clinkering kiln. The calcines should be free, or substantially so, of carbon dioxid. If the calcines be well calcined however, the temperature at which they are delivered to the clinkerer is not of great moment and the point of incipient clinkering may swing back and forth between the two kilns. It is this lack of any necessity for a delicate balancing of conditions between the calcining and clinkering zones which offers one of the greatest advantages of my 2-kiln process as constructed with the prior art in which one source of heat was used for both zones.

With the cement material well calcined, there is no great liability of dusting and when it is at the point of incipient sintering or softening it of course does not dust at all. It is this which constitutes the main reason for preferring that the calcines be introduced into the clinker kiln in a stage of incipient sintering. But since the clinker kiln under the present invention is run with a very small flame and little rush of flame gases there is little liability of much dusting in any event. Calcination however is preferably completed in the calcining kiln since evolution of carbon dioxid requires a good volume of heat and a plentiful supply of diluent gases to sweep it away; neither being conditions existing in the clinker kiln under the present invention.

In the accompanying drawings I have illustrated, more or less diagrammatically, certain embodiments of my invention as described.

In this showing:—Figure 1 is a view, mostly in vertical longitudinal section, of a complete clinker plant; Fig. 2 is a plan view, partly in horizontal section, of the clinkerer of Fig. 1; Fig. 3 is a similar view of a modification; and Fig. 4 is a view of another modification.

In Fig. 1, element 1 designates a calcining kiln, fragmentarily and diagrammatically shown. As represented, it is provided with gas-firing means 2, drawing a supply of heated air through conduit 3 from a clinker pit 4. It is provided with the usual housing 5 provided with a duct 6 for removal of calcines. From this duct, the calcines drop into a hopper 7 and are fed forward into the clinkering kiln 10 substantially like that shown in my Patent No. 879,448. In this kiln the calcines become clinkered and finally emerge therefrom, dropping through conduit 11 into a clinker pit. Facing the open mouth of the kiln is a housing 12 carrying the firing means. These consist, as shown, of a coal burning nozzle, 13, fed with powdered fuel from hopper 14 and air under pressure

from pipe 15. A contained jet nozzle 16 in this pipe allows the air to carry the coal forward by induction. On either side of this burner is a flue, respectively 17 and 18, communicating with regenerators 19 and 20 (see Fig. 2). In Fig. 1, flue 18 (not shown) communicates with downtake 21 having dust door 22 at its base and uptake 23, tapped at 24 to permit withdrawal of a portion of heated air to feed fan 25 (see Fig. 2) through valved pipe 26. A similar pipe 27 taps the uptake from flue 17. For the sake of simplicity both these pipes are shown provided with hand valves. A valved inlet 28 permits the supply of cool air to the fan to temper the hot air from the regenerator flues. On the blast side of the fan is a pipe 15 communicating with the burner as already described.

Returning to regenerator 20, this is provided with the usual checkerwork 29. The other regenerator, 19, is the same in structure. Both regenerators are provided with a passage 30 leading to stack 31 past butterfly valve 32 of the usual construction.

The operation of the described structure is obvious. It being the object to produce a relatively small, intensely hot flame in the clinker kiln, the coal blast is fed with hot air taken from the regenerator which is heating air, its temperature being regulated if necessary by admission of a little cool air from 28. But a fraction of the air necessary to burn the coal however can be sent in with it in this manner and the residue is introduced from flue 17 or flue 18, according to which regenerator is in the air heating phase. This air sweeps alongside the coal jet, producing a quick and hot combustion and the hot flame gases recure and sweep back through the other flue and into and through the other regenerator, heating it up, and ultimately pass to the stack.

In the organization shown in Figs. 1 and 2, the calcining kiln is gas fired, and the clinkerer is coal fired. The gas employed for the calciner may advantageously be producer gas and the hot air employed to burn it may advantageously be somewhat diluted with products of combustion, since producer gas and hot air give a shorter flame than is advantageous in calcinations. The firing in this kiln should be so controlled that the calcines emerge at or near the clinkering temperature since this reduces the consumption of fuel in the clinkerer. Such calcines should be as free as possible of carbon dioxid since this interferes with the normal operation of the clinkerer.

Fig. 3 shows, partly in horizontal section and partly in plan, a rather diagrammatic view of a clinkerer fired by a coal jet in the manner described. In this structure, the clinkerer 40 in lieu of being the peculiar kiln of my former patent is built like an ordi-

nary rotary. At its lower end it enters an ordinary housing 41 pierced for admission of coal burner pipe 42, fed from hopper 43, and for hot air ducts 44. At its upper end, 5 it is provided with means for introducing calcines, shown in dotted lines at 45, and enters a stationary housing 46. From this housing pass outward two similar flues 47 and 48, controlled by water-cooled valve 49, 10 shown as closing 47. These two flues enter regenerators, respectively 50 and 51, near the top thereof. At the base of the regenerators flues 52 and 53 lead to stack 54, being controlled by dampers 55 and 56. 15 Tapped into these flues are valved air ducts 57 and 58 deriving air from blower 59. Tapped into the flues 47 and 48 are air conduits 60 and 61 leading to the burning means of the kiln. By appropriate manipulation 20 of the valves, the hot waste gases can be sent through either flue, 47 or 48, into the corresponding regenerator, heating it up and passing thence to the stack while the other regenerator can have air passed through it 25 to conduit 44.

Fig. 4 shows diagrammatically, the combination of a calciner 70 coal fired by burner 71, fed by hopper 72 and fan 73, with a clinkerer 74, calcines being delivered to the 30 latter through hopper 75 and conveyor 76 delivering into hopper 77 having a conduit 78 leading down through a housing 79 at the upper end of the clinker kiln, said housing being provided with stack 80 for removal of waste gases. At the lower end of the clinkerer is the usual housing 81, pierced for coal burner 82, fed by hopper 83 and fan 84. As stated, the consumption of fuel in the clinkering kiln in operating a plant according to my process, is very little and, as 35 shown in this figure, regenerative means may be dispensed with for the coal-fired clinkerer. Use of such regenerative means is, however, 40 advantageous.

45 In the operation of the clinkerer shown in Fig. 1, the coal is burned by air alternatively entering at one side and at the other, thereby somewhat changing the localization of the intense combustion. From the conditions existing in the kiln, this makes little 50 difference but, if it be desired, when the valves of the regenerators are reversed and the place of entry of the hot air is changed the direction of rotation of the kiln can also 55 be reversed.

While the calcining kiln may be coal-fired, as shown in Fig. 4, yet I regard it as preferable to heat it with gas as gas heating is better adapted to calcining conditions. With 60 producer gas and hot air, particularly if the air be somewhat diluted with products of combustion, a flame particularly adapted to calcination may be obtained. With coal firing means very intense temperatures are apt 65 to be attained, and these are not desirable in

the calcining kiln in the present invention since it is the object to transfer the high-temperature operations to the special clinkering kiln. In the calcining kiln it is desirable to do no substantial amount of clinkering though the materials should emerge from it thoroughly calcined and substantially free from carbon dioxide, and, preferably, at or near the point of incipient clinkering. 70

75 The use of gas in the calciner and of coal in the clinkerer enables a very good and exact production of the different thermal conditions in the two kilns: the gas producing a diffused heating at comparatively low 80 temperature for calcining and a little coal jet burning with superheated air enabling the production of the few heat units and high temperature of the clinkerer.

What I claim is:—

85 1. A clinker making plant comprising a rotary separately fired calcining kiln and a rotary clinkering kiln provided with means for burning finely divided concentrated fuel therein by the aid of air regeneratively 90 heated by the waste gases of such clinkering kiln.

95 2. A clinker making plant comprising a rotary separately fired calcining kiln and a rotary clinkering kiln provided with means 100 for producing therein a relatively small flame of powdered coal in aerial suspension burning with the aid of air regeneratively heated by the waste gases of such clinkering kiln.

105 3. A clinker making plant comprising a rotary clinkering kiln, means for introducing calcined cement material at the point of incipient clinkering thereinto, means for producing a jet of fine fuel in aerial suspension in such kiln, waste gas removing means for such kiln, regenerators interposed between the kiln and waste gas removing means and means for passing air through such regenerators into proximity with such 110 jet of fine fuel.

115 4. A clinker making plant comprising means for producing calcined cement material at or near the clinkering point, a rotary clinkering kiln receiving such calcined material, means for producing a flame jet of fine fuel in aerial suspension in the mouth of such kiln, regenerative means for producing a current of hot air on one side of such flame and regenerative means removing waste 120 gases at the other side of such flame.

125 5. A clinker making plant comprising means for producing calcined material at or near the clinkering temperature, a rotary clinkering kiln having a closed upper end, means for introducing said calcined material into such upper end, means for feeding a jet of powdered coal into the lower end, a pair of regenerators having flues opening into said lower end on either side of said 130

- coal jet and means for alternately passing waste gases from the kiln through each of such regenerators to exit and air through the other of said regenerators into the kiln.
5. A clinker making plant comprising a rotary separately fired calcining kiln and a rotary coal-fired clinkering kiln receiving calcines therefrom.
6. A clinker making plant comprising a rotary gas fired calcining kiln and a rotary coal fired clinkering kiln receiving calcines therefrom.
7. A clinker making plant comprising a rotary calcining kiln provided with means for firing the same with gas and hot air and a rotary clinkering kiln receiving calcines therefrom and provided with means for firing with fine fuel in aerial suspension and heated air.
20. 9. The process of producing cement clinker which comprises producing calcined cement material at or near the clinkering point by a separate source of heat, transferring such calcined material to a rotary cement kiln and there completing the clinkering by a flame jet of fine fuel in aerial suspension burning with the aid of air regeneratively heated by the waste gases of such kiln.
10. The process of producing cement clinker which comprises passing pulverulent cement material through a separately fired rotary calcining kiln to produce calcines at or near the point of incipient clinkering, transferring such calcines to another rotary kiln and there completing the clinkering by a flame jet of fine coal in aerial suspension.
11. The process of producing cement clinker which comprises passing pulverulent cement material through a gas fired rotary calcining kiln to produce calcines at or near the point of incipient clinkering, transferring such calcines to another rotary kiln and there completing the clinkering by a flame jet of powdered coal burning in aerial sus-
pension.
45. 12. The process of producing cement clinker which comprises passing pulverulent cement material through a gas fired rotary calcining kiln to produce calcines at or near the point of incipient clinkering, transferring such calcines to another rotary kiln and there completing the clinkering by a flame jet of powdered coal burning in aerial sus-
pension with the aid of air regeneratively heated by the waste gases of such second kiln.
13. The process of producing cement clinker which comprises producing calcined cement material at or near the point of incipient clinkering by one source of heat, transferring said calcined material to a rotary kiln and there completing the clinkering by a recurring flame of powdered coal in aerial suspension burning with the aid of regeneratively heated air.
14. The process of producing cement clinker which comprises producing calcined cement material at or near the point of incipient clinkering by one source of heat, transferring such calcined material to a rotary kiln, introducing a jet of fine coal in aerial suspension into the mouth of said kiln, introducing a current of heated air at one side of said jet to burn said coal and removing the waste flame gases at the other side of said jet and removing the clinker from said kiln after completion of the clinkering.
15. In a clinker making plant, means for producing calcines, a rotary kiln receiving calcines therefrom, means for supplying calcined cement materials thereto, means for producing a flame of fine fuel in aerial suspension in the mouth of the kiln and regenerative means abstracting heat from the waste gases from such flame and returning it to air fed to such flame.

In testimony whereof, I affix my signature in the presence of two witnesses.
